CLAIM

I claim the ornamental design for a food utensil mount, as shown and described.

DESCRIPTION

FIG. 1 is a perspective view of a first embodiment of a food utensil mount showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an additional perspective view thereof including several food items skewered on utensils of the first embodiment of the food utensil mount.

In these drawings, the solid lines illustrate the claimed ornamental design, whereas the broken lines illustrate unclaimed subject matter and form no part of the claimed design.
